CASTING TRIMMING

Karl F. Dailey, Cleveland, Ohio

Application February 17, 1934, Serial No. 711,802

6 Claims. (Cl. 29—33)

This invention relates to production of steel ingots or the like by means including a centrifugal casting machine such as those disclosed in my copending applications, Serial No. 680,564, filed July 15, 1933 and another filed of even date herewith. The objects of the invention are generally to provide an arrangement for producing a straight clean ingot ready to be rolled into billets or the like, from the curved product of the casting machine, in a most efficient manner, particularly as to number and scope of operations required, heat losses and other considerations which will become apparent.

More specifically an object of the invention is to make novel provision for straightening of the casting and for trimming its scrap crop part from the remaining metal.

The exact nature of this invention together with further objects and advantages thereof will be apparent from the following description taken in connection with the accompanying drawings, in which Fig. 1 is a typical section of casting; Fig. 2 is a plan layout view of a form of apparatus which might be employed in practicing the invention, showing below the break indicated, complete apparatus for a single casting, and thereabove additional apparatus for another similar casting; and Fig. 3 is an enlarged detail in vertical section, as in the plane of line 3—3, Fig. 2, views being of a conventionalized nature.

According to the invention, a casting of ring form is provided, by centrifugal apparatus, which may be such as that disclosed in my said copending applications. The casting is preferably an endless or continuous ring for simplicity of mold, ease of handling, and speed and simplicity of subsequent operations; but it may be split at one location at its periphery to be an integral whole but without endless continuity, or indeed, the mold might be so arranged that the casting constitute only an arcuate section substantially less than 360° in extent.

At any rate, and particularly where the ring form is endless, the casting will have certain shrinkage during cooling, and due to such shrinkage, its inner peripheral part will be subjected to compressive stresses from its outer peripheral part. Such stresses in the casting considered, may have been enhanced by the application of mechanical pressure to the inner periphery before complete solidification, as by means fully illustrated and described in the latter of my said copending applications.

The casting contemplated is a large one, as in the order of eight inches by eight inches, and

twelve or more feet in diameter. Obviously, a casting so made will have a scrap crop part at its inner periphery.

A feature of this invention is that the casting be of such characteristics and typical section that the scrap crop shall be a relatively thin one, of greater radial dimension and lesser longitudinal dimension relative to the casting axis than has heretofore been the practice in the art. Several sections having such desired characteristics are illustrated in my first said copending application, but only a single one of elementary nature is here indicated, as in Fig. 1, at A, A', Fig. 2, and A, Fig. 3. This casting form is obviously, in characteristic section, thinner at its inner radial extremity than at zones of greater radius.

According to this invention, after such a casting has been produced it is removed from the mold as soon as possible after its solidification, and as soon thereafter as possible the operations to be described are performed thereupon; so that all subsequent operations are completed while a major or very substantial amount of the casting heat is retained, whereby heat losses are avoided and much of the necessary working force is reduced.

If the casting has been produced in the form of an endless ring, the scrap crop may be removed by a turning operation, involving a cutting tool moving concentrically relative to the ring. Obviously the work of thus trimming off the crop will be relatively light, corresponding with the relative thinness of the crop.

My preferred practice is, however, that the trimming of the scrap crop follow other operations.

The first of these operations, following the removal of the casting from the mold, is to split the casting if it has not been produced in split form. For this purpose, a table or platform 1 may be provided, having vertically extending rollers 2 arranged to locate the casting on the table or platform, and preferably having radially disposed horizontally extending rollers 3 on which the casting will bear. Associated with the table 1 is a hot saw generally indicated at 4 and having a blade 5 adjustable in the suitable clearance slot indicated in the table 1, for slitting the casting positioned on the table by the rolls 2. The saw adjustment is here indicated as pivotal about the center line shown.

The next step is to open the ring sufficiently to permit one end of it to somewhat overhang the other end. For this purpose, as here indicated, a

cylinder 6 may be provided on the table having the rod 7 of its piston carrying a pivotally mounted cross arm 8, which cross arm carries at its ends the rolls 9. Obviously an outward stroke of the 5 piston will effect spreading of the ring as indicated in Fig. 2, the rolls 2 within the ring cooperating to prevent bodily motion of the ring.

Before the opening operation the ring is adjusted on the rolls 3 generally about its own axis 10 to bring one end of the split ring to be engaged by the rolls 9, and as the rolls 9 move against the ring to open it, the head 8 will provide a differential rocking action effective between the rolls 9 which latter will move somewhat along the ring 15 as the piston advances; so that, though the ring because of its heat be somewhat soft, its opening operation will produce no sharp bend therein.

After opening, the ring is again axially adjusted upon the rolls 3 to assume the position of 20 ring A, Fig. 2, with its opened end adjacent a fixed stop shoe 10. It will be appreciated that the described rotational adjustments of the ring upon the rolls 3 may be accomplished either by 25 a crane or the like, or might be accomplished by drive of the rolls 3.

The shoe 10 positions the ring end immediately ahead of two pairs of rolls 11, both driven as by the conventionally indicated driving motor 12a through gear box 12. These rolls are of a form 30 corresponding with the sectional shape of the casting, to engage the casting between them and advance it, with straightening effect.

That the casting may be fed from the position indicated at A in Fig. 2 to the first pair of rolls 11, 35 a bulldozer shoe 13 is movably mounted on the table 1 by a link 14 at one end, pivoted at 15, and has actuating connection with the piston rod 7, as by the link 16 below the table. Once the casting is in the position of A, Fig. 2, the cylinder 6 is reversed, pulling the bulldozer 13 up against the casting to jam its open end between the first pair 40 of rolls 11. It will be appreciated that the cylinder 6 is double-acting, preferably actuated by hydraulic pressure, under the control of the operator.

45 Once the rolls 11 have taken hold of the end of the casting, they advance the casting from the table 1 with an unwinding effect, and into the first pair of a train of rolls generally indicated at 17, all driven on axes at right angles to the rolls 11. The first pair of rolls 17 may be similar to the rolls 11, that is, need merely have driving effect upon the casting. The succeeding rolls of train 17, however, are provided with pinching or cutting edges 18, as indicated in Fig. 3, of progressively greater depth as indicated in Fig. 2. The cutting edges are disposed to remove from the casting as the casting passes through the train of rolls, the scrap crop which was formerly at the inner radius of the casting and now as the 55 casting is straightened, lies along one side edge thereof. The last pair of rolls 17 need comprise simply a single cutter alone, as indicated in Fig. 2, which cutter will comprise a shearing edge by which the scrap crop will be completely removed.

60 The casting thus emerges from the train of rolls 17, straightened and stripped of its scrap crop, and still retaining a substantial amount of heat from the mold whence it came. It will be appreciated that in practice the entire process described takes place in a very few minutes, the progress of the casting itself through the rolls being very rapid once it is commenced.

65 Since it is preferable to produce two ring castings simultaneously in the casting machine, preferably the table 1 is made of double length to ac-

commodate two castings at once, as indicated in Fig. 2, the supplementary part of the table constituting essentially a duplicate of the part already specifically described. For clearance reasons it is preferable that the second hot saw 4a be 5 set to one side as indicated. A corresponding stop shoe 10a and an additional set of feeding and straightening rolls 11a are provided for the second casting, the rolls being driven as by the gear head indicated conventionally at 12b from the motor 12a. By this dual arrangement, the second casting may be fed into its rolls 11a to immediately follow the first casting, that is, as the first casting is unrolled from its circular form and straightened, and its following end passes between its straightening rolls 11, immediately thereafter the second casting on the second part of the table, and which has meanwhile been split and opened, may be started into its rolls 11a. Of course the second casting upon emerging from the 20 rolls 11a passes between the rolls 11 before entering the train of rolls 17.

What I claim is:

1. Apparatus of the class described, comprising a table, roller means thereon arranged to receive and position a ring casting and to permit rotative adjustment of the latter, means for splitting said casting in supported position, and means associated with said table for opening an end of said casting by expansive forces effective within the ring confines and for providing a feeding advance of said end and comprising a reversible actuator and a pair of members to be actuated thereby, one within said ring for opening the latter and one outside said ring for feeding advance of the opened ring end. 25

2. Apparatus of the class described, comprising a table, roller means thereon arranged to receive and position a ring casting and to permit rotative adjustment of the latter, means for splitting said casting in supported position, and means associated with said table for opening an end of said casting and for providing a feeding advance of said end and comprising a reversible fluid actuator and a pair of members to be actuated thereby, one within said ring for opening the latter and the other a shoe outside said ring floatingly mounted for feeding advance of the opened ring end. 40

3. Apparatus of the class described, comprising a table adapted to receive and support a plurality of ring castings in horizontally spaced relation and to permit independent rotative adjustment of said castings, means associated with said table for splitting said castings, means for opening the ends of said castings, and means for providing feeding advance of said ends in a common direction, whereby said castings may be split and opened individually and received successively from said table by a single stationary unit for 55 performing subsequent operations upon said castings. 60

4. Apparatus of the class described, comprising a table adapted to receive and support a plurality of ring castings in horizontally spaced relation and to permit independent rotative adjustment of said castings, means associated with said table for splitting said castings, means for opening the ends of said castings, means for providing feeding advance of said ends in a common direction, 65 and means for straightening the said ends as the latter are so advanced. 70

5. Apparatus of the class described comprising a table adapted to support a split ring casting, means extending from said table adjacent oppo- 75

site inner portions of the casting, and including stationary means at one side of the casting, means at the other side of the casting and mounted for movement toward and from said stationary means, and power means for adjusting the movable means from the stationary means to open the casting.

6. Apparatus of the class described comprising a table adapted to support a split ring casting, means extending from said table adjacent op-

posite inner portions of the casting, and including stationary means at one side of the casting, means at the other side of the casting and mounted for movement toward and from said stationary means, and power means for adjusting the movable means from the stationary means to open the casting, said means comprising rollers spaced circumferentially of the casting to provide distribution of the opening forces. 5
